(57) **CLAIM**

The ornamental design for a license plate frame, as shown and described.

DESCRIPTION

FIG. 1 is a front perspective view of the license plate frame of the present invention;

FIG. 2 is a front elevation view of the license plate frame of the present invention;

FIG. 3 is a left side view of the license plate frame of the present invention;

FIG. 4 is a right side view of the license plate frame of the present invention;

FIG. 5 is a top plan view of the license plate frame of the present invention; and,

FIG. 6 is a bottom plan view of the license plate frame of the present invention.

The rear view is not part of the claimed design.

The portions of the license plate frame shown in broken lines form no part of the claimed design.
